UNITED STATES PATENT OFFICE.

LEWIS SHARPS BIXLER, OF KENTON, OHIO, ASSIGNOR TO KENTON HARDWARE CO.,
OF KENTON, OHIO, A CORPORATION OF OHIO.

DESIGN FOR A TOY AUTO CIRCUS CALLIOPE.

Application filed March 25, 1924. Serial No. 9,065. Term of patent 14 years.

To all whom it may concern:

Be it known that I, LEWIS S. BIXLER, a citizen of the United States, and a resident of Kenton, in the county of Hardin and State of Ohio, have invented a new, original, and ornamental Design for Toy Auto Circus Calliopes, of which the following is a specification, reference being had to the accompanying drawing, forming part thereof.

The figure is a perspective view of a toy auto circus calliope, showing my new design.

I claim:

The ornamental design for a toy auto circus calliope, as shown.

LEWIS SHARPS BIXLER.
